CLOCKCASE

Philip L. Garland, Jr., Louisville, Ky., assignor to
General Electric Company, a corporation of
New York

Application February 9, 1953, Serial No. 23,487

Term of patent 14 years

(Cl. D42—7)

To all whom it may concern:

Be it known that I, Philip L. Garland, Jr., a citizen of the United States, residing at Louisville, county of Jefferson, State of Kentucky, have invented a new, original, and ornamental Design for a Clockcase, of which the following is a specification, reference being had to the accompanying drawing, forming a part thereof.

In the drawing:

Fig. 1 is a front perspective view of a clockcase, showing my new design;
Fig. 2 is an elevational view of the side opposite that shown in Fig. 1;
Fig. 3 is a rear elevational view; and

Fig. 4 is a top plan view.

I claim:

The ornamental design for a clockcase, as shown.

PHILIP L. GARLAND, JR.
